US0D1016584S

(12) **United States Design Patent** (10) **Patent No.:** **US D1,016,584 S**
(45) **Date of Patent:** **** Mar. 5, 2024**

(54) **HEAD PORTION OF A RATCHET WRENCH**

(71) Applicant: **Hong Ann Tool Industries Co., Ltd.,**
Taichung (TW)

(72) Inventor: **Cheng-Wei Su**, Taichung (TW)

(73) Assignee: **Hong Ann Tool Industries Co., Ltd.,**
Taichung (TW)

(**) Term: **15 Years**

(21) Appl. No.: **29/802,827**

(22) Filed: **Aug. 9, 2021**

(51) LOC (14) Cl. **08-05**

(52) U.S. Cl.

USPC **D8/25**; D8/21

CLAIM

The ornamental design for a head portion of a ratchet wrench, as shown and described.

DESCRIPTION

FIG. 1 is a perspective view of a head portion of a ratchet wrench showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view showing the utilization of head portion of a ratchet wrench.

The broken line showing of a ratchet wrench is included for the purpose of illustrating portions of the article in which the design is embodied and forms no part of the claimed design. The shaded surfaces and the solid lines represent the claimed portions of the design.

1 Claim, 8 Drawing Sheets
